UNITED STATES PATENT OFFICE.

GEORGE HAVELL AND ALFRED G. WILLIAMS, OF NEWARK, NEW JERSEY.

DESIGN FOR A BICYCLE-LAMP.

SPECIFICATION forming part of Design No. 26,763, dated March 16, 1897.

Application filed October 15, 1896. Serial No. 609,030. Term of patent 3¹ years.

To all whom it may concern:

Be it known that we, GEORGE HAVELL and ALFRED G. WILLIAMS, citizens of the United States, residing at Newark, county of Essex, State of New Jersey, have invented a certain new and useful Design for Bicycile-Lamps, fully described and represented in the following specification and the accompanying drawings, forming a part of the same.

In the drawings, Figure 1 is a rear elevation, Fig. 2 a side elevation, and Fig. 3 a plan, of a bicycle-lamp embodying our design.

The lamp-body embraces the following features: the horizontal cylinder A, having convex lens projection B at the front end and at the rear end the convex protuberance C, joined to the body by the cavetto or concave molding c, thus forming an ogee curve at the base of the protuberance and a sharp corner at its junction with the cylinder A.

From the lower side of the cylinder A projects the round neck D for supporting the oil-cup, and from the top the flaring funnel E, having cap molded at the edge with the

smooth ovolo or convex molding F and terminated on top by the flat cylindrical boss G. The neck D and the parts represented above the same constitute the body, and the portion below such neck constitutes the oil-cup.

The oil-cup is formed with horizontal fillet H around the middle and smooth ovolo moldings above and below the same, the upper molding I curving inward to the neck D and the lower molding J curving inward to a flat cylindrical boss K.

Having thus described the design, what we claim herein is—

The design for a bicycle-lamp, substantially as herein shown and described.

In testimony whereof we have hereunto set our hands in the presence of two subscribing witnesses.

GEORGE HAVELL.
ALFRED G. WILLIAMS.
